ROTARY PUMP, COMPRESSOR, AND THE
LIKEMiller R. Hutchison, Jr., Madison, N. J., assignor
to Multicycol Pump & Engine Corporation, New
York, N. Y., a corporation of New York

Application January 21, 1933, Serial No. 652,861

7 Claims. (Cl. 103—124)

This invention relates to machines and apparatus in the nature of rotary pumps.

Special objects of the invention are to secure a relatively great working displacement per revolution in a compact small unit and free of the usually attendant high rubbing velocities of rotary pumps, compressors and the like. Other desirable objects and the novel features of construction, combinations and relations of parts by 10 which the desired results are attained will appear as the specification proceeds.

The drawings accompanying and forming part of the specification illustrate certain practical commercial embodiments of the invention, it being understood that the actual physical structure may vary, all within the intended broad scope of the claims.

Fig. 1 is a broken longitudinal sectional view of the invention embodied in the form of a pump.

Fig. 2 is an end elevation of the same.

Fig. 3 is a cross-sectional view as on substantially the plane of line 3—3 of Fig. 1.

Fig. 4 is an enlarged broken sectional detail of the cam and rocker formation.

Fig. 5 is a broken end view showing particularly the supporting cylinder.

The desired large working displacement is attained in this invention through the cooperative combination of a series of preferably symmetrically grouped hollow rockers 7 and concentrically related cam or impeller 8. This cam is shown as of generally triangular shape having three equi-distant rounded lobes 9, connected by plane flanks 10.

The rockers are shown as of somewhat greater than semi-cylindrical form disposed in seats 11, which are of greater than semi-cylindrical outline, so as to actually retain and support the rockers. The cavities in the inner exposed faces of the rockers are shown as curves 12, substantially concentric with the nose curves of the cam lobes, joining at the ends with convex follower curves 13, for closely riding the cam faces. The clearance or lack of clearance at 14, between the rocker hollows and cam lobes may vary in different designs, depending on the nature of the fluid and the use of the apparatus. For handling oils, and particularly furnace oils, in which certain amount of impurities may be present, a slight clearance is desirable, such as that indicated in the illustration, Fig. 3.

The rockers may be shaped in continuous lengths or rods of the cross-section illustrated, produced by casting, molding, rolling or machining and cut in the proper lengths for individual

rockers and the material may be metallic or non-metallic. Certain composition materials, such for example, as that known in the trade as "Micarta" are desirable, because they are light and strong and possess a certain degree of resiliency, enabling them to closely follow the cam contour and to accommodate themselves to any slight irregularities there may be in such contour. These composition rockers may be accurately molded to exact size, operate with but slight friction and the wear is low.

The rocker seats are provided in the present disclosure in a cylindrical support 15, which serves, in addition, as the spacing member between the end heads 16, 17 of the machine, the latter being secured by screws 18, in abutting engagement with the shouldered seats 19, 20, in the ends of the cylinder. Annular gaskets are shown provided at 21, about these abutting joints between the ends of the cylinder and the end heads of the machine.

Bearings 22, 23, are provided in the end heads for the shaft extensions 24, 25, of the cam or impeller.

In the present disclosure, the cam or impeller is hollowed out as indicated at 26, to form an inlet 25 for the fluid and consequently the shaft extension 22 is tubular in form. The opposite shaft extension 25 may be solid and be equipped with a key 27, or the like, for a driving gear or pulley.

For the entry of fluid into the tubular end of 30 the cam, the surrounding bearing of the end plate 16 is shown as having a tubular screw threaded extension 28, adapted to receive suitable pipe connections.

For convenience of mounting and dismounting, 35 both bearing extensions of the end plates are shown in the form of hubs 29, which may be rotatably supported as for torque measuring purposes and the like, and which in the case of a permanent installation, as here illustrated, may be keyed at 30, in split supporting standards 31, having the cap portions 32, removably secured as by bolts 33, which construction enables quick mounting or unmounting of the apparatus as a unit. The bearing hub at the drive end of the 45 machine may carry a suitable shaft packing, such as indicated at 34, with an adjustable gland nut 35.

The combined rotary and oscillatory movements of the cam and rockers are utilized in the illustration to accomplish the necessary valving functions.

Thus the cam is shown as having inlet ports 36, extending from the hollow interior out through the lead faces of the lobes, direction of rotation 55

considered, Fig. 3, and the rockers are shown as having aligned ports or passes 37, therethrough for cooperation with ports 38, opening out through the backs of the rocker seats.

5 In a construction which is relatively long for its diameter, the several sets of ports may be discontinuous in the form of longitudinally aligned slots, as indicated in Fig. 1, but it will be realized that for a short form of construction, a single set 10 of slots will suffice.

10 For manifolding purposes, the outlet ports 38 and the cylinder are shown as all connected by a surrounding casing shell 39, which may have an outlet, such as indicated at 40, and preferably located at the bottom to serve as a drain and to 15 carry out any dirt in the oil or other fluid.

15 In the detail view, Fig. 4, a preferred design 20 of cam and rocker form is illustrated, wherein it will be seen that the rocker center 41, substantially coincides with the point of the cam lobe and that the follower faces 13, are struck from centers 42, located equal distances to opposite sides of the rocker center on the same diametrical line 43, passing through that center. The nose of 25 the cam is shown as an arc struck from a center 44, and joined with the flanks of the cam by slightly greater arcs struck from the center 45. This construction and relation provides a desirable cam contour and smooth-following rocker 30 action. The cam ports 36 are here shown as offset substantially parallel with a radial line 46, drawn from the shaft center 47 and the rocker ports 37 are shown as inclined in the same general direction, that is rearwardly, in the direction 35 opposite to direction of cam movement. In the position of parts appearing in Fig. 4, this effects opening of the rocker ports to the outlet ports approximately at or slightly following closure of the cam ports.

40 The entry of liquid through the center and outward flow through the cam makes use of centrifugal force and enables the cam to operate as an impeller. This action is further facilitated, because of the continued outward flow through the 45 rocker and cylinder ports to the surrounding manifold. The distribution of ports in both the cam and the rockers, enables these being made of ample size and the relative placing of same to effect desired valving and pressure results. The 50 rocker seats of more than semi-cylindrical form brace and confine the rockers full length and enable these being relatively light and with considerable port areas therein.

55 The impeller cam and the rockers are finished with their ends flush and have ample sealing surfaces in engagement with the end walls of the casing structure and the rockers and cam design maintain constant engagement with the cam face, so that no packing is required for handling fluids, 60 such as fuel oil, except possibly for the usual shaft packing here illustrated.

65 While a three lobe cam and four cooperating rockers constitute a desirable combination of these elements, it will be understood that the cam may vary in the number of lobes and that the number of rockers employed may differ for various sizes of machines, materials handled, pressures developed, volume, speed, special purposes of the machine, etc.

70 The rocker seats being of greater than semi-cylindrical dimensions, provide supports for the rockers extending inwardly as close as possible to the cam and hence afford proper backing for the rockers, preventing them from binding under the thrust of the cam lobes. These seats

will hold the rockers in place after removal of the impeller cam and they provide extended bearing surfaces affording ample sealing contact between rockers and seats. Also the greater than semi-cylindrical seats prevent distortion, particularly in the longer lengths of rockers and produce a better valving operation, where the rockers are utilized as here, to serve also as valves. The convexly rounded tips or ends of the rockers enable them to smoothly follow the cam face 10 and to maintain proper seal at all times without undue friction. If desired, the ends of the rockers and impeller may be sealed by a special end plate having a self-adjusting "floating" engagement with the same. Other changes and modifications may be made, within the true intent and scope of the following claims.

5 What is claimed is:

1. A machine of the character disclosed, comprising in combination, cooperatively engaged relatively rotatable cam and rocker members, the engaging faces of said rockers having cavities cooperating with the cam face and end seals between the cam and rocker members to form variable displacement chambers and said cam and 20 rocker members having valve ports for effecting transfer of fluid to and from said chambers in the movements of the same.

2. In combination, a hollow rotatable impeller cam having a port therethrough, a plurality of 30 rockers each having a cavitated chamber-defining face cooperating with said cam and having a port opening away from said chamber-defining face, end seals between the ends of the rockers and the sides of the impeller cam completing 35 variable displacement chambers between the cam and rockers and whereby upon rotation of the cam, transfer of fluid may be effected between the cam and rockers.

3. In combination, a support having circular 40 seats with ports therethrough, circular ported rockers operating in said seats and having exposed hollow faces, a ported lobed member cooperating with the hollow faces of said ported rockers, end seals between the sides of said lobed 45 member and the ends of said hollow rockers completing variable displacement chambers between said lobed member and rockers and said lobed member being rotatable to effect or enable displacement of fluid to and from said chambers 50 through said lobed member and rockers.

4. In combination, a support having a cylindraceous seat with a port opening therethrough, a cylindraceous rocker journaled for rocking movements in said seat and having a port to register with said seat port in the rocking movements of the same, a rotary lobed member engaging said rocker, said rocker having a concave face opposed to the lobed member and said latter member having a port to register with the concavity of the rocker member and end seals between the ends of the rocker and sides of the lobed member completing a variable displacement chamber between the rocker and lobed member, whereby upon rotation of said member, fluid can be passed to and from said chamber.

5. In a machine of the character disclosed, the combination of a generally cylindrical support having longitudinally extending cylindraceous seats, cylindraceous rockers journaled in said seats and having inwardly disposed concave faces, a lobed member journaled to cooperatively engage the concave face portions of said rockers, a chamber surrounding said cylindrical support and having end walls sealing the chambers de- 70 75

fined between the rockers and lobed member and porting connections between the rockers and said surrounding chamber for passing fluid from said chambers in rotation of said lobed member.

- 5 6. A machine of the character disclosed, comprising a casing having end bearings, a rotatable cam in said casing and having shaft ends journaled in said bearings, one of said shaft ends being of tubular form and the cam having a hollow interior in communication with said tubular shaft, said cam being further ported from said hollow interior through the outer surface of the same, a rocker journaled in the casing and having a concave face portion engaged with the cam face, said rocker having a passage extending therethrough from the concave face of the same and the supporting portion of the casing having a port for registry with said passage.

7. A machine of the character disclosed, comprising a casing having a generally cylindrical wall, a rocker journaled in said casing and having a hollow face coextensively related to said cylindrical wall, said rocker and casing having companion valve elements to function in the oscillating movements of said rocker and an impeller cam operating in said casing and having a lobe or lobes engaging said cylindrical wall of the casing and both edges of said rocker at opposite sides of said hollow face of the rocker and said casing having end walls sealing the spaces defined between the hollow rocker and cam whereby upon rotation of the cam displacement of fluid may be effected in respect to said chamber. 5 10 15
